UNITED STATES PATENT OFFICE.

MORRIS HANNA, OF NEW YORK, N. Y.

TOY BOAT.

1,407,410.

Specification of Letters Patent. Patented Feb. 21, 1922.

Application filed August 30, 1920. Serial No. 406,941.

To all whom it may concern:

Be it known that I, MORRIS HANNA, a citizen of the United States of America, and a resident of New York, county of New York and State of New York, have invented certain new and useful Improvements in Toy Boats, of which the following is a full and clear specification.

The object of this invention is to provide 10 a simple toy boat provided with means for propelling it, the propelling means being adapted to be wound up by hand or a suitable hand implement, as more fully herein-after set forth.

15 In the drawing—

Fig. 1 is a perspective view of a toy boat constructed in accordance with my invention, the propelling arrangement being adapted for marine propellers;

20 Fig. 2 is a similar view, foreshortened, showing the invention applied to an aerial propeller type of boat.

Referring to Fig. 1, *a* designates the hull of the boat, which may be of any suitable 25 construction and proportions and which in the present instance is shown as constructed of a single piece of wood, properly shaped or carved. Fastened to the stern of the boat, upon its upper side, is a bar *b*, whose ends 30 project outwardly beyond the sides of the hull and are bent upwardly, the extreme ends of this bar being bent into U-shape to form separated bearing supports for the propeller-shafts *c*. These propeller-shafts *c* 35 lie parallel to each other and each is provided with a marine propeller at its rear end.

An open eye *d* is fastened in the bow of the boat at each side thereof, these 40 eyes extending upwardly and outwardly from the bow. These eyes are respectively connected to the forward ends of the propeller-shafts by means of an endless rubber band *f*, each propeller-shaft being provided with an open eye *e* to enable the band 45 to be readily attached thereto. The ends of the bands are attached to eyes *d* and *e* by being simply slipped thereinto so that, it will be observed, the bands may be readily 50 removed from the eyes.

To charge the propeller mechanism of the boat with power, it is simply necessary to rotate the propellers in the opposite di-

rection to thereby twist the rubber bands and put them under a torsional strain, whereby when the propellers are released the tendency of the bands to untwist will rotate the propellers in the opposite direction and thus propel the boat. The bands may be twisted directly by hand or through the medium of a hand-operated twisting appliance which will twist the bands with equal tension, to thereby ensure an equal development of power in the two propellers and thus ensure a straightforward movement of the boat. While it is desirable to thus wind the bands to an equal tension to thereby drive the boat in a straight line, it is one of the advantages of my device that the bands may be twisted to an unequal tension where it is desired that the boat shall be propelled in a curved path. The driving of the boat in a straight line by equally tensioning the bands is ensured by employing a pair of propellers and arranging them 70 symmetrically on the hull—that is, an equal distance from the longitudinal center line of the hull. It will be observed further that by arranging the rubber bands at a point above the upper surface of the hull they 75 will be suspended in a plane above the surface of the water so as to prevent the bands dragging in the water and thus retarding the boat. When the bands are twisted by means of a hand implement, it will be 80 understood that the forward ends of the bands are removed from the eyes *d* and engaged with the hooks of the twisting implement; and then after the bands are equally 85 twisted to the desired degree the looped forward ends are slipped out of the twister-hooks and into the eyes *d*, immediate rotation of the propellers being prevented by grasping the hull at the rear end thereof in such manner that the hand will prevent 90 the propellers rotating. When the boat is placed in the water and the hand is removed, the propellers will immediately begin rotation and continue to rotate until the bands are completely untensioned.

It will be understood that it is within the broader spirit of my invention to employ but a single propeller and propeller-band arranged over the longitudinal center of the boat; and it will be further 105 understood that, as shown in Fig. 2, I

may extend the propeller-supports high enough from the deck of the boat to employ air propellers instead of the marine propellers shown in Fig. 1.

5 It will be observed further that by employing power means located above the surface of the deck of the boat, I am enabled to employ a marine propeller of the semi-submerged type, this type having been 10 found by me to be especially efficient in a toy of this character. This arrangement of power means also enables me to avoid the necessity of employing a hollow watertight hull, as there is no need for housing 15 the propeller bands within the hull; it will be observed that I can use the type of hull illustrated, which is the flat or skimmer form of hull, a type very inexpensive to manufacture.

20 The nature and scope of the invention having been thus indicated and its preferred

embodiment having been specifically described, what is claimed as new is:

A toy boat comprising a hull, propellers mounted at one end of said hull having 25 forwardly-extending shafts formed into hooks at their free ends, supports for said propeller-shafts extending upwardly and outwardly from the hull, whereby the shafts are supported in a plane above the top surface of the hull and above the water-line 30 of the boat, and a separate driving means for each of said propellers embodying an elastic band adapted to be twisted under tension and which extends substantially the 35 length of the hull and secured at its ends to the front end of the hull above the water-line and propeller-shaft respectively.

In testimony whereof I hereunto affix my signature.

MORRIS HANNA.
